Primary Examiner — Ian Simmons*Assistant Examiner* — Keith Frank(74) *Attorney, Agent, or Firm* — Harness, Dickey & Pierce, PLC(57) **CLAIM**

We claim the ornamental design for a bottle, as shown and described.

DESCRIPTION

FIG. 1 is a top perspective view of a bottle, in accordance with a first variant;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a top perspective view of a bottle, in accordance with a second variant;

FIG. 8 is a front elevation view thereof;

FIG. 9 is a rear elevation view thereof;

FIG. 10 is a right side elevation view thereof;

FIG. 11 is a left side elevation view thereof; and,

FIG. 12 is a top plan view thereof.

Throughout the figures, where shown, the stippled, broken and/or diagonal shading lines are for illustrative purposes only and form no part of the claimed design. The broken lines in the drawings showing the bottle illustrate the portions of the bottle that form no part of the claimed design.

1 Claim, 12 Drawing Sheets(56)
